UNITED STATES PATENT OFFICE.

DAVID L. STRONACH, OF COLUMBIA, SOUTH CAROLINA.

DESIGN FOR A PIPE.

Application filed April 18, 1925. Serial No. 13,159. Term of patent 14 years.

To all whom it may concern:

Be it known that I, DAVID L. STRONACH, a citizen of the United States of America, residing at Columbia, in the county of Richland and State of South Carolina, have invented a new, original, and ornamental Design for Pipe, of which the following is a specification, reference being had to the accompanying drawings, forming a part thereof.

The figure is a perspective view showing my new design.

I claim:

The ornamental design for a pipe as shown.

D. L. STRONACH.
